UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

INTERLOCKING MACHINE FOR RAILROADS

Application filed August 26, 1929. Serial No. 388,437.

This invention relates to interlocking machines, and more particularly pertains to indication latch mechanisms used therein.

In one type of interlocking system, it has been proposed that the control levers shall have two extreme or full positions, that is, a full normal position and a full reverse position with each of these full positions preceded by their corresponding intermediate steps which are conveniently termed indicating positions, by reason of the indication of the fact that the traffic controlling function has completed its operation which is required before the control lever is allowed to be moved to a corresponding full position. Such indication positions serve the purpose of maintaining the mechanical interlocking between levers in a locked condition until the indication of the completed operation of the traffic controlling function is received.

In this type of interlocking system, the locking means, for preventing the control lever from being moved out of an indicating position to its corresponding full position, is commonly known as an indication latch mechanism, which is released by the energization of a suitable electromagnet associated therewith.

Heretofore, it has been necessary in the control of the switch machines at the two ends of a cross over, in order to make it possible for the operator to control both switch machines with one operation, to provide duplicate control levers with one lever rigidly connected to the other. Although such an arrangement eliminates the number of control operations for the operator, it does not reduce the size of the interlocking machine, because two lever spaces are required to provide the necessary two indication latch mechanisms.

With the above considerations in mind, it is proposed, according to the present invention, to provide a type of indication latch mechanism adaptable for multiple combinations, so that more than one traffic controlling function may be operated from the circuit controllers of one control lever with separate indication latch mechanisms, corresponding to each traffic controlling function, governing

the movement for that particular control lever.

A further object is to provide a compact and sturdy mechanism so organized that the locking means preventing the movement of the control lever at certain times are slidably connected to the frame members, thus eliminating the major stresses from the pivoted members of the mechanism.

It is also an object of this invention to provide such an indication latch mechanism in a unit structure which may be easily disengaged from its control lever for removing it from the interlocking machine without disturbing other indication latch mechanisms, or any other devices.

Various other objects, purposes and characteristic features will be in part pointed out and in part obvious as a description of the invention progresses.

In describing the invention in detail, reference will be made to the accompanying drawings in which like reference characters refer to like objects, and in which:

Fig. 1 is a side elevation of a single indication latch mechanism constructed according to the present invention and mounted upon the frame of an interlocking machine in coacting relation with an interlocking control lever;

Fig. 2 is a side elevation of a single indication latch mechanism constructed according to the present invention and shown in its normal position with certain parts removed;

Fig. 2A is a side elevation of a single indication latch mechanism constructed according to the present invention and shown in its reverse indicating position with certain parts removed;

Fig. 3 is a cross section of a single indication latch mechanism taken on line 3-3 of Fig. 2;

Fig. 4 is a cross section of a single indication latch mechanism taken on line 4-4 of Fig. 2;

Fig. 5 is a cross section of a single indication latch mechanism taken on line 5-5 of Fig. 2;

Fig. 6 is a side elevation of a multiple or

double indication unit latch mechanism constructed according to the present invention with certain parts removed;

Fig. 7 is a cross section of a multiple indication latch mechanism taken on line 7-7 of Fig. 6;

Fig. 8 is a cross section of a multiple indication latch mechanism taken on line 8-8 of Fig. 6;

Fig. 9 is a cross section of a multiple indication latch mechanism taken on line 9-9 of Fig. 6;

Fig. 10 is a top view of a spring biased wedge supporting means;

Fig. 11 is an end view of the spring biased wedge supporting means of Fig. 10.

Fig. 12 is a side view of spring biased wedge supporting means of Fig. 10.

A single indication latch mechanism is one which is associated with a control lever that operates a single traffic controlling function, while a double indication latch mechanism is one associated with a control lever operating two traffic controlling functions. It is of course understood, in the case of the double indication latch mechanism, that both of the indication magnets must be energized thus releasing each locking means before the movement of the lever is allowed. As the double indication latch mechanism is a modification of the single indication latch mechanism, the latter will be described in detail with the modifications of the multiple unit pointed out as the description of the present invention progresses.

With reference to the drawings, Fig. 1 shows a single indication latch mechanism IL mounted within an interlocking machine in a coacting position relative to a lever L, in a manner such for example as set forth in my pending application Ser. No. 380,418 filed July 23, 1929 and entitled "Interlocking machines". However, in order to show the relation between the various parts of an indication latch mechanism IL, and the interlocking lever L with which it is associated, it is pointed out that the indication latch mechanism IL is mounted upon an interlocking frame bed member 5 at the left hand end and is held in position by a spring biased wedge supporting means or detent D at the right hand end. The lever L is provided with a slot 6 which receives a projection 9¹ integral with an actuating cam member 9 included within the indication latch mechanism IL.

The indication latch mechanism includes two frame members 7 and 8 (see Fig. 3) which are of irregular shape so as to provide the necessary recesses, pivot points, bushings and guides for various operating members. In Fig. 1, the frame member 7 has not been shown in position, so that the various moving parts are shown as mounted upon the frame member 8.

Along the top portion of the frame member

8 a guiding slot 8^a (see Fig. 5) is provided for an actuating cam member 9, having a projection 9¹ which suitably fits into the slot 6 of control lever L as heretofore stated. Also, along the lower portion of the frame member 8 another slot 8^b is provided for a detaining cam member 10 which is rigidly attached to the cam member 9 by a plate 11. This plate 11 is permanently riveted to the cam members 9 and 10 by rivets 12. Thus, any motion transmitted from the lever L to the projection 9¹, thereby causes the cam members 9 and 10 to move in a reciprocating manner in respect to the frame members 7 and 8.

Between the slots 8^a and 8^b provided for the cam members 9 and 10, there are projections 13, 14, 15, 16, 17, 18 and 19 which are an integral part of frame member 8, and serve to inclose and form guides for certain movable parts. The projections 14, 15, 16 and 17 form part of a guiding slot 8^c (see Figs. 2 and 4) which is perpendicular to the slots 8^a and 8^b and furnish a guide for a movable detent 20 which may move in a reciprocating manner in respect to the frame member 8. This movable detent 20 is of sufficient thickness to allow a latch 21 (see Fig. 4) to pass through a slot 20^a. Thus, with the latch 21 pivoted upon a pin 22 which is secured to the frame member 8 and passes into a suitable bushing of frame member 7, the movable detent 20 may be operated in a vertical direction in a manner that the latch 21 will turn upon the pin 22.

A latching pawl 23 is pivoted upon a pin 24 which is secured to the frame member 8 and passes into a suitable bushing in the frame member 7. This latching pawl 23 is biased to an extreme position by a coil spring 25 being mounted upon a pin 26, which pin is secured to the projection 18.

The projections 18 and 19 form a part of a vertical guiding slot for a safety dog 27. This safety dog 27 is provided with a suitable recess for a coil spring 30, thus supplying means to bias a steel ball 31 against a plate 32, which plate 32 is secured to the safety dog 27 by screws 33. The plate 32 contains a counter sunk opening to permit a part of the steel ball 31 to sufficiently pass through to engage a slight depression in the frame member 8 for a purpose to be herein-after explained.

The latch 21, the latching pawl 23 and the safety dog 27 are held into position against the frame member 8 within their slots by a plate 34 which fits within suitable recess within the projections 13, 14, 15, 16, 17, 18 and 19 and is secured into position by screws 35 which thread into the projections 13 and 19. With the latch 21 thus held into position the movable detent 20 is also provided with retaining means.

A link 40 is provided with a pin 41 which

fits into a suitable recess 8^d in a manner to allow the link 40 to move in a reciprocating vertical direction to engage the safety dog 27. The guiding slot for this link 40 is provided by the frame member 8 and the cam member 10 thus providing that the link 40 shall move within certain predetermined limits. Also, there is a recess 40^a in the link 40 for receiving the circular head of a plunger 42 (see Fig. 1), which is attached to an armature 43 of an indication magnet IM.

From Figs. 3 and 5 it may be seen that the frame member 7 holds the cam members 9 and 10 in a guiding slot 7^a in as much as the frame member 7 is secured to the frame member 8 by bolts 48 and 49, these bolts being provided with suitable lock washers. Spacer members 44 are provided for the bolts 48 in as much as the frame members 7 and 8 do not come into contact with each other at these points.

With reference to Figs. 3 and 4, it is noted that the pins 22 and 24 extend from the frame member 8 through the frame member 7, thus making necessary the slots 11^a and 11^b in the plate 11, (see Fig. 1), so that the lever L may move the cam members 8 and 10 in a reciprocating manner. Thus, the pins 22 and 24 furnish limits for the movement of the cam members 9 and 10. Also, a slot 11^c is provided to prevent the interference of the screw 35 with the movement of the plate 11.

The actuating cam member 9 is provided with a projection having the cam surfaces 9^a and 9^c which come into engagement with the cam surfaces 20^b and 20^d of the detent 20 at certain times to force the detent 20 into a slot or depression in the detaining cam member 10. This slot or depression within the cam member 10 is provided with cam surfaces 10^a and 10^b which at certain times engage the cam surfaces 20^c and 20^d of the detent 20.

The actuating cam member 9 also has another projection having cam surfaces 9^b and 9^d which engage at certain times the projection 23^a of the latching pawl 23 and simultaneously therewith the projection 27^a of the safety dog 27. The actuation of this safety dog 27 in a downward direction (see Fig. 2) forces it into a slot or depression provided in the detaining cam member 10. This slot in the detaining cam member is provided with limits 10^c and 10^d which come into contact with the safety dog 27 at the same time that the cam surfaces 10^a and 10^b come into contact with the movable detent 20, with the exception of course of those times that the safety dog is actuated to an upper position for releasing the lever L.

The detaining cam member 10 also has a projection having vertical surfaces 10^e and 10^f which engage the link 40 whenever said link 40 is actuated to an upper position. Thus, it is seen that the actuating cam member 9 has cam surfaces which actuate or operate the detent 20, the pawl 23 and the safety

dog 27 to their actively detaining positions, while the detaining cam member 10 has cam surfaced and limiting projections which actively engage the detent 20, the safety dog 27 and the link 40 to detain or prevent the movement of the lever L at certain times as hereinafter explained.

When the lever L is operated toward the left (see Fig. 1), it can only be operated as far as the reverse indication position which causes the parts to assume positions as shown in Fig. 2A, during which movement the cam member 9 moves toward the left (see Fig. 2) until the cam surface 9^a comes into contact with the cam surface 20^b of the detent 20 to force the movable detent 20 to a lower extreme or active position within the cam member 10. As soon as the movable detent 20 assumes a lower position, so that the latch 21 is in a position, as shown in Fig. 2A, the cam surface 9^b comes into contact with the right hand cam surface of projection 23^a and the right hand cam surface of projection 27^a, which forces the latching pawl 23 to engage or lock the latch 21. Also, the safety dog 27 is caused to assume a position, as shown in Fig. 2A, so that after the latching pawl 23 is in a locking position, the lever L is prevented from further movement by the cam surface 10^a coming into contact with the cam surface 20^c of the locked movable detent 20, and the limiting projection 10^d coming into contact with said safety dog 27.

The energization of the indication magnet IM, which is accomplished by the completion of the movement of the traffic controlling device, operated by the lever L, pulls the armature 43 in an upward direction which motion is transmitted through the plunger 42 through the sliding link 40 to the safety dog 27. With the safety dog 27 actuated to an upper extreme or inactive position, the latching pawl 23 is caused to release the latch 21, so that the detent 20 no longer actively engages the detaining cam member 10 but is also forced to an inactive position by further movement of the lever L toward the left or full reverse position which may now be accomplished. The latching pawl 23 is held in this position biasing the spring 25 by the engagement of the steel ball 31 into the depression provided for it in the frame member 8 as shown in Fig. 3.

Should the indication magnet IM for some unauthorized cause continue to be energized the lever L is prevented from being returned to its normal indication position thence to its full normal position, because of the projecting surface 10^f of the detaining cam member 10 which engages the movable link 40.

The operation of the lever L to the normal indicating position causes the cam surface 9^c to engage the cam surface 20^d, causing the movable detent 20 to assume an active position at which time the cam surface 9^d engages

the left hand cam surface of the projection 23^a and the left hand cam surface of the projection 27^a to cause the latching pawl 23 to lock the detent 20 and the safety dog 27 to engage the limit 10^d. The lever L is thus locked in the normal indicating position as explained for the reverse indicating position with further movement toward the full normal position being prevented by the cam surface 10^e engaging the cam surface 20^e of the movable detent 20, and the engaging of the limiting surface 10^d with the safety dog 27. The energization of the indication magnet IM in a similar manner releases the locking of the movable detent 20 and disengages the safety dog 27 from the limiting surface 10^e, so that the full normal position of the lever L may be attained.

It will be noted, that the movement of the lever L from one indicating position to the other indicating position is always possible except when the indication magnet IM is energized at which time the limiting surfaces 10^f and 10^e, engage the slidable link 40, with the lever L in the reverse indicating position or in the normal indicating position respectively.

With reference to Figs. 6, 7, 8 and 9, one modification of the present invention is shown providing a double indication latch mechanism, that is, a mechanism requiring an indication from each of two traffic controlling functions before the control lever which it governs may be moved to a full position.

This double indication latch mechanism IL¹ is the same size unit as the single indication latch mechanism and may be mounted in a coacting position relative to the lever L of Fig. 1 in a similar manner to the single indication latch mechanism as shown. In place of the indication magnet IM, there are two such magnets IM¹ and IM² provided, which have armatures 50 and 51 respectively. These armatures 50 and 51 operate plungers 52 and 53 respectively being so positioned on each side of the center line of the magnets as to operate their respective links 54 and 55, which links release their respective locking mechanisms in the same manner as the link 40 of the single indication latch mechanism.

The double indication latch mechanism is provided with a two part frame having right and left hand frame members 56 and 57 both of which are similar to the frame member 8 as may be seen by the comparison of Fig. 9 with Fig. 5.

The frame member 56 provides guiding slots for the actuating cam member 58 and the detaining cam member 59, while the frame member 57 provides guiding slots for the actuating cam member 60 and the detaining cam member 61. The actuating cam member 58 and the detaining cam member 59 are rigidly connected together as well as the actuating cam member 60 and the detaining

cam member 61, with the plate 62 used to interconnect the four cam members in position (see Figs. 8 and 9). The actuating cam members 58 and 60 are identical in shape to the actuating cam member 9 of Fig. 2, with the actuating cam member 60 shown in Fig. 6. Also, the detaining cam members 59 and 61 are identical in shape with the detaining cam member 10 of Fig. 2, with the detaining cam member 61 shown in Fig. 6.

The actuating cam member 58 and the detaining cam member 59 coact with a detent 63, a latch 64, a latching pawl 65, a safety dog 66, and a link 55 in a similar manner as set forth for the coacting operations of the actuating cam member 9 and the detaining cam member 10 as heretofore explained. Similarly a detent 67, a latch 68, a latching pawl 69 and a safety dog 70 are provided in the frame member 57 and are shown in Fig. 6. These various interrelated moving parts which are mounted upon their respective right and left hand frame members 56 and 57, are held into position by plates 71 and 72 which are secured by suitable screws 73. The frame members 56 and 57 are connected by the bolts 74 and 75.

It is thus seen that there is a complete locking mechanism on each side of the plate 62 which engages the lever L in a manner to govern its movement in accordance with the locked condition of each set of locking devices.

From Fig. 6 it will be noted that there are slots 62^a, 62^b and 62^c in the plate 62 for allowing movement of the various cam members although the pins 76 and 77 are used to mount the latches 64 and 68, also the latching pawls 65 and 69 respectively.

It is thus seen that this type of mechanism is very adaptable for multiple indication latch mechanisms, making it possible to include two indication latch mechanisms, that is, a multiple unit, in the same space occupied by a single indication latch mechanism.

As both the single and double indication latch mechanism units are the same size and are interchangeable the same mounting means may be used for securing both forms in their proper position in respect to the lever L.

With reference to Fig. 1 it is seen that the spring biased wedge shaped detent D secures the mechanism in position by clamping the plate 78 against the frame 88 of the interlocking machine and the frame members 7 and 8 of the indication latch mechanism IL. The spring 79 then pushes the wedge 80 in such a manner that there is a constant tension upon the indication latch mechanism. The bolt 81 passes through the center of the wedge 80, spring 79 and plate 78 so that movement upon a horizontal plane is prevented. The wedge 80 is slidably attached to the plate

78 by rivets 83 and 82 (see Figs. 10, 11 and 12).

5 The advantage of such a spring biased wedge mounting means is, that each indication latch mechanism is tensioned with a uniform force so that the frame of the interlocking machine is not distorted from its proper position. It is noted, that should the wedge member 80 be secured in position by 10 tightening the bolt 81, that there is no definite limit to determine when a proper tensioning force is applied. Hence, there would be a varying stress throughout the length of the interlocking machine.

15 Thus, an indication latch mechanism has been shown and described, which is complete in a unit structure and may be easily placed in a coacting position with its control lever. Also, means has been provided for 20 mounting the mechanism in such a manner that all mechanisms have a uniform supporting tension upon them. The present disclosure has further provided a type of locking means which directly transmits all forces, 25 which may be applied to the control lever, directly to the frames of the indication latch mechanism, thus removing the stresses which have heretofore been applied to the pivot points of such mechanisms. Also, this type 30 of locking means readily adapts itself to multiple indication latch mechanisms as is shown by the modification which is constructed according to the present invention.

35 An indication latch mechanism has been shown and described in a rather specific manner, however, it is to be understood that various modifications and adaptations may be applied to such a mechanism constructed according to the present invention without de- 40 parting from the scope of the invention, as set forth in the appended claims.

Having described my invention, I now claim:—

1. In an interlocking machine, a control 45 lever, a guiding support member for said control lever, and a detachable unit indication latch mechanism including, a detent means capable of preventing the final movement of said control lever to its extreme positions, actuating means rendering said detent means active, latching means locking said detent means in an active condition, and means rendered active by the application of electrical energy to unlock said latching 50 means.

2. In an interlocking machine, a control lever, a guiding support member for said control lever, and a detachable unit indication latch mechanism including, two reciprocating cam members operated by said control lever, a detent capable of preventing final movement of said cam members, means moving said detent to an active position before completion of movement of said control lever to a new operating position, locking means

caused to lock said detent in an active position by completion of movement of said control lever to a new operating position, and means rendered active by application of electrical energy to unlock said locking means. 70

3. In an interlocking machine, a control lever, a guiding support member for said control lever, and a detachable unit indication latch mechanism including, a detaining cam member actively engaging said control 75 lever, an actuating cam member actively engaging said control lever, a detent capable of actively preventing final movement of said detaining cam member, a safety dog capable of actively preventing final movement of said detaining cam member, a latching lever actively engaging said detent, a locking pawl locking said detent in an active position by locking said latching lever each time said detent assumes an active position, a releasing link being capable of actuating said locking pawl and said safety dog for moving said detent and said safety dog to inactive positions, and also being capable of preventing intermediate movement of said control lever when in an actuating position by actively engaging said detaining cam member. 80

4. In an interlocking machine for railroads, a control lever, and an indication latch mechanism for preventing final movement of said control lever until after actuation of said mechanism, and for preventing intermediate movement during actuation of said mechanism with said indication latch mechanism including, a detaining cam member, an actuating cam member, a slidably operable detent, a slidably operable safety dog, a latching lever, a locking pawl biased to a locking position, a releasing link, and means operably retaining said safety dog in a released position in opposition to said biased locking pawl until said safety dog is actuated by said actuating cam member. 95

5. In an interlocking machine for railroads, a control lever, locking means preventing final movement of said control lever including, a detaining cam member, an actuating cam member, a slidably operable detent, a slidably operable safety dog, a latching lever, a locking pawl, releasing means including an electro responsive device, a releasing link, and said safety dog, and means preventing intermediate movement of said control lever during actuation of said releasing means including said detaining cam member and said releasing link. 100

6. In an interlocking machine, a control lever, a guiding support member for said control lever, and a detachable unit indication latch mechanism including, a safety dog capable of preventing final movement of said control lever, actuating means rendering said safety dog active, means rendered active by the application of electrical energy for controlling said safety dog to an inactive posi- 115 120 125 130

- tion with said means including, an electro responsive device, and a releasing link, means preventing intermediate movement of said control lever during actuation of said safety dog to an inactive position including said releasing link, and means operably retaining said safety dog in an inactive position until acted upon by said actuating means.
7. In an interlocking machine, a control lever, a guiding support member for said control lever, a detachable unit indication latch mechanism, and means including a spring biased wedged member for mounting said indication latch mechanism in a coacting position relative to said control lever.
8. In an interlocking machine, a control lever, a guiding support member for said control lever, a detachable indication latch mechanism, and means including a wedge member, a coil spring for biasing said wedge member, a limiting plate, and a bolt attached to said guiding support member upon which said limiting plate is secured by a nut, and upon which said wedge member is slidably mounted, whereby said indication latch mechanism is mounted in a coacting position relative to said control lever.
9. In a detachable unit indication latch mechanism for interlocking machines, a two part casing, an actuating cam member slidably mounted within said two part casing, means for actively connecting said actuating cam member with a control lever of an interlocking machine, a detaining cam member rigidly connected to said actuating cam member, an electro-responsive device, locking means preventing movement of said control lever to an extreme position except when actuated by said electro-responsive device, locking means preventing movement of said control lever from one intermediate position to another intermediate position when said electro-responsive device is in an actuating condition.
10. In an interlocking machine, a control lever, a guiding support member for said control lever, a detachable indication latch mechanism including, a two part casing, a plurality of actuating cams and a plurality of detaining cams actively connected to said control lever, a plurality of detents and a plurality of safety dogs for preventing the final movement of said control lever, means locking said detents in active positions each time said detents are operated to active positions by their respective actuating cams, a plurality of electro magnets, means releasing a particular detent and a particular safety dog upon energization of a particular electro magnet, and means preventing movement of said control lever between intermediate positions while any one of said electro magnets is energized, whereby said control lever is prevented from completing its final move-

ment until all of said electro magnets have been momentarily energized.

11. In an interlocking machine, a control lever, a guiding support member for said control lever, and a detachable unit indication latch mechanism including, a plurality of detent means each being capable of preventing the final movement of said control lever to its extreme positions, actuating means rendering said plurality of detent means active, a plurality of latching means locking their respective one of said detent means in an active condition, and a plurality of means rendered active by the application of electrical energy to unlock their respective latching means, whereby said control lever is prevented from movement to its extreme positions until after all of said detent means are controlled to active conditions.

12. In an interlocking machine, a control lever, a guiding support member for said control lever, and a detachable unit indication latch mechanism including, a plurality of reciprocating cam members operated by said control lever, a plurality of detents each capable of preventing final movement of said cam members, means moving each of said detents to active positions before completion of movement of said control lever to a new operating position, a plurality of locking means each caused to lock its respective one of said detents in an active position by completion of movement of said control lever to a new operating position, and a plurality of means each being rendered active by application of electrical energy to unlock its respective one of said locking means, whereby said control lever is prevented from being operated to extreme positions until all of said locking means have been unlocked.

13. In an interlocking machine, a control lever, a guiding support for said control lever, and a detachable unit indication latch mechanism including, a plurality of detaining cam members actively engaging said control lever, a plurality of actuating cam members actively engaging said control lever, a plurality of detents capable of actively preventing final movement of their respective one of said detaining cam members, a plurality of safety dogs being capable of actively preventing final movement of their respective one of said detaining cam members, a plurality of latching levers actively engaging their respective one of said detents, a plurality of locking pawls each one locking its respective one of said detents in an active position by locking its respective one of said latching levers each time its respective one of said detents assumes an active position, a plurality of releasing links each being capable of jointly actuating one of said locking pawls and one of said safety dogs respectively for controlling said safety dog and its respective one of said detents to inactive positions, and also

being capable of preventing intermediate movement of said control lever when in an actuating position by actively engaging said detaining cam members, whereby said control lever is prevented from movement to either extreme position from the corresponding intermediate position until all of said detents and all of said safety dogs have been actuated to inactive positions, and whereby said control lever is prevented from being moved from one intermediate position to another intermediate position during actuation of any one releasing link.

10 14. In an interlocking machine, in combination, a control lever, a guiding support member for said control lever, a unit indication latch mechanism member for the control lever, and means detachably mounting the latch member in relation to the control lever.

15 15. In an interlocking machine, in combination, a control lever, a guiding support member for said control lever, a unit indication latch mechanism member for the control lever, and elastic tensioning means detachably mounting the latch member in relation to the control lever.

20 In testimony whereof I affix my signature.
WINTHROP K. HOWE.
